UNITED STATES PATENT OFFICE.

ALEXANDER GORDON, OF DETROIT, MICHIGAN.

CIGAR-BUNCHING MACHINE.

SPECIFICATION forming part of Letters Patent No. 657,596, dated September 11, 1900.

Application filed November 11, 1897. Serial No. 658,196. (No model.)

To all whom it may concern:

Be it known that I, ALEXANDER GORDON, a citizen of the United States, residing at Detroit, in the county of Wayne and State of Michigan, have invented certain new and useful Improvements in Cigar-Bunching Machines, of which the following is a specification, reference being had therein to the accompanying drawings.

10 The invention consists in the new construction, arrangement, and combination of parts, with the object in view of making a better working machine than those heretofore constructed, all as more fully hereinafter described and specifically pointed out.

In the drawings, Figure 1 is a side elevation of my cigar-bunching machine. Fig. 2 is a vertical cross-section in a plane parallel with Fig. 1 and substantially on line $x-x$ in Fig. 3. Fig. 3 is a vertical transverse section substantially on line $x-x$ in Fig. 1. Fig. 4 is a diagrammatic perspective view of a portion of the top of the machine with one side of the frame removed. Fig. 5 is a cross-section of Fig. 4, substantially on line $y-y$ thereof. Figs. 6 and 7 are diagrammatic representations of Fig. 5, showing the parts in different positions of operation. Fig. 8 is a cross-section of the pocket of the bunching-apron and one of its swinging wing-guides. Fig. 9 is a cross-section on line $z-z$, Fig. 3, looking toward the left. Fig. 10 is a cross-section on line z^2-z^2 , Fig. 3, looking toward the right. Fig. 11 is a cross-section on line $z'-z'$ in Fig. 3 looking toward the right.

The bunch is rolled by a bunching-apron A, (particularly shown in cross-section in Figs. 5, 6, and 7,) and both ends of this apron are preferably attached at the same point, which is the roll a. This bunching-apron passes around a roll b, stationarily journaled in the frame, thence around the stationary bunching-roll B, thence during the operation of the machine, as in Fig. 5, around the bunch to be rolled, thence over the oscillating segmental bunching-table C, thence over a roll c, carried by the table, and thence back to the roll a. A small idler-roll b' keeps the bunching-apron pressed against the face of the bunching-table. The roll a is journaled in an oscillating frame d, which is carried by

the bunching-table, with which it has a pivotal connection at e, and f is a spring to normally hold this oscillating frame against the fixed stop h. This roll a forms the means for 55 adjusting the length of the bunching-apron, and to this end it is preferably provided at one end with a ratchet with which co-operates a pawl, so that by turning the roll in one direction or the other the apron can be lengthened or shortened at will, according to the requirements of the bunch. The bunching-table is carried by radial arms g, terminating at the inner end in bosses h' h², which are sleeved upon a shaft E, journaled transversely in the frame, one of the bosses h² being provided with a gear-pinion i, by means of which motion is communicated to the bunching-table, as shown in Fig. 3.

F is an apron-tightener consisting of a roll 70 journaled in the arms of an oscillating frame k, which oscillating frame is carried by radial arms j, secured upon the shaft E, motion being communicated to the apron-tightener by a pinion l upon the shaft E. (See Fig. 3.) 75

G is a binder-table normally held in the position shown in dotted lines in Fig. 5. This table is supported in front of the bunching-table by means of rounded pins m in the curved guide-slots m', which guide-slots are 80 formed in the frame of the machine and permit the movement of the table during the operation from the position shown in dotted lines into the position shown in full lines in Fig. 5, this motion being accomplished by an 85 oscillating lever n. (See Figs. 2 and 4.)

H is a pressure-roll movably supported in a frame o in front of the bunching-roll B and adapted to yield vertically.

I is a bunch-receiver normally projecting 90 in front of the bunching-table below the table G, as shown in Figs. 4 and 5. This bunch-receiver is formed with two vertical sides p p', the latter of which is slidably supported by springs upon the bed-plate p². The latter is 95 provided at its ends with supporting-pins engaging into guide-slots q in the sides of the frame, as shown in Figs. 1 and 2, whereby in operation the receiver is adapted to move from the position shown in Figs. 4 and 5 into 100 the position shown in Fig. 7, this movement being brought about by means of the oscil-

lating levers r , pivotally secured to the side of the frame and connecting with the bunch-receptacle by the links r' .

J J are two guide-fingers engaging into the ends of the fold in the bunching-apron. These guide-fingers are free to oscillate on pivot-pin s , pivotally secured in the sides of the frame in such a manner that in the operation of bunching the side flanges C' of the table engage the guide-fingers, and they are thereby carried into the folds of the bunching-apron opposite the ends of the bunch, and thereby prevent any extended distortion or displacement of the same.

15 Upon the top of one of the sides of the frames is supported or formed the lower platen K of a mold-press. Through this lower platen extend two vertical guide-rods L L, which at the lower end are united by a cross-bar M and have sleeved upon the upper ends the follower-plate N, which is yieldingly held in position by means of coil-springs t, adjustably secured by the nuts t'.

The motion of the different parts is produced in the following manner: O is a transverse shaft journaled in the lower end of the frame, by means of which motion is communicated to the machine. This shaft has at one end a clutch-pinion u, through which motion is communicated at will to a gear-wheel v upon a main drive-shaft P, as shown in Fig. 3. This drive-shaft is provided with a toothed wheel Q, with which a dog R is adapted to engage under control of the operator. The dog R is pivotally secured to a cam-disk S, (see Figs. 3 and 10,) which is sleeved upon the shaft P, and the shaft carries with it another cam-disk T. The cam-disk S is provided with suitable cam-grooves 40 into which engages a wrist-pin of an oscillating segmental rack U, and the cam T is provided with a cam-groove into which engages a wrist-pin on the oscillating segmental rack U', all so arranged that by the engagement 45 of the dog R into the toothed wheel Q the cams S and T revolve together and impart an oscillating reciprocating movement to the segmental racks U U', which in turn communicates an oscillating motion to the bunching-table and the apron-tightener F. The toothed gear-wheel Q revolves continuously; but the dog R, which engages therewith, is automatically tripped as soon as it has performed one complete revolution. To this end the dog R

50 has a wrist-pin R', which engages into a groove R² of the cam-disk R³. This cam-disk R³ is loosely sleeved upon the shaft P and is pivotally connected at a point of its periphery by a link R⁴ with the treadle-level V, which 55 is under control of the operator. The cam-groove R² is concentric with the shaft, except for the short eccentric portion R⁵, which is sufficiently eccentric to hold the dog R out of engagement with the toothed wheel P. 60 However, when the treadle V is depressed by the operator the cam-disk R³ is partially revolved, sufficiently to engage the dog R into

the concentric portion R² of the guide-groove, and thereby throw it into engagement with the toothed wheel Q, and the dog R will 70 thereby be compelled to perform one complete revolution, or until its wrist-pin re-enters the eccentric portion R⁵ of the guide-groove. To withdraw the dog more fully from engagement with the toothed wheel Q, 75 I provide the disk R³ with a projection R⁶, which is adapted to strike against the fixed stop R⁷ on the frame, and diametrically opposite to the projection R⁶, I connect the disk with the coil-spring R⁸. These parts operate 80 in the following manner: As before stated, when the operator depresses the treadle V the disk R³ is sufficiently turned to throw the dog R into engagement with the toothed wheel, and the dog will then be held by the 85 concentric portion of the groove R² in engagement with the toothed wheel Q. During such travel (the operator having withdrawn his foot from the treadle V) the frictional contact of the wrist-pin of the dog R in the 90 guide-groove R² will naturally turn the disk R³ until its projection R⁶ is arrested by contact with the stop R⁷; but the moment the dog R, after having completed one revolution, is thrown out of engagement with the 95 toothed wheel Q the spring R⁸, being under tension, will rock the disk R³ sufficiently back again to throw the dog R still farther away from the teeth of the wheel Q to prevent any possibility of scraping and damaging the teeth 100 by too-close proximity, as would happen otherwise.

The operation of the press is accomplished by means of a toothed wheel Q' on the opposite end of the shaft P, which transmits motion to cam-wheel S' through the medium of a dog in precisely the same manner as motion is transmitted, as before described, from the toothed wheel Q to the cam-wheel S, the only difference being that the guide cam-groove 105 R², as shown in Fig. 11, has two eccentric portions R⁵ diametrically opposite each other, whereby the depression of the treadle V imparts only half of a revolution to the cam S'. The cam-disk S' has a cam-groove into which 110 engages a wrist-pin W on the cross-bar M, all so arranged that one-half of the revolution of the cam-disk S' will draw down the follower N upon the molds and tightly clamp them, while by the other half of the revolution the follower is lifted off again to release the molds. The cam-disk T is provided with other suitable cam-grooves or cam-guides to 115 impart the necessary oscillating motion to the oscillating levers r and n, which are 120 coupled in pairs connected by suitable transverse shafts and impart the required oscillating motion to the table G and bunch-receiver I.

In practice, the parts being arranged as 130 shown and described, the operation is as follows: The parts being in the normal position shown in Figs. 2 and 4, the operator puts the necessary amount of filler to make a bunch

into the pocket of the bunching-apron and lays the binder on the table G, so that it will slightly project over the edge, as shown in Fig. 4. Then the operator imparts motion by depressing the treadle V momentarily, the dog R being thereby thrown into engagement with the toothed wheel Q, which imparts motion to the cam-wheels S and T. The cam-wheel S has a cam-groove which actuates the segmental rack U in advance of the segmental rack U', and thus the bunching-table begins to move first into the position shown in Fig. 5, without the tightener-roll as yet having moved from its normal position. When this position of the bunching-table is obtained, the bunch is wholly inclosed within the pocket and the table now momentarily stops, while the tightener-roll F begins to move by the engagement of the cam-disk S with the segmental rack U, the relative position of the racks at this moment being shown in Fig. 9. The roll while the table is thus stationary moves from the position shown in Fig. 5 into the position shown in Fig. 6, with the consequent result that the slack is taken out of the bunching-apron and the bunch is compressed as far as is necessary, the pressure being equalized by the yielding connection of the roller a with the bunching-table. When the relative position of the parts, as shown in Fig. 6, is obtained, the bunching-table and the tightener-roll move in unison together and continue to move until the final position in Fig. 7 is obtained. During this movement the bunch is rolled in the well-known manner in the pocket of the bunching-apron, and simultaneously therewith the binder is wrapped around it. This binder has been brought into the position shown in Fig. 5 during the first movement of the bunching-table by the actuating connections described, and in this position the loose overhanging front edge, being pressed on by the roller H against the bunching-table, will naturally follow the apron and be wrapped around the bunch, and then the table, having passed beyond the bunching-roller, will drop into the bunch-receiver I, which meanwhile has been moved by its particular connection into the position shown in Fig. 7. The parts then all return again to their normal position, which permits the operator to take the bunch out from the receiver I and place it in the mold for pressing. When the number of molds for which the press is qualified is filled, the operator puts his foot on the treadle V', and thereby operates the press. The first half of the revolution raises the follower sufficiently to allow the operator to remove the molds previously inserted, which are now removed and the newly-filled molds put in place. By setting his foot again upon the treadle V' the next half of the revolution brings the follower down the necessary distance to clamp and hold the newly-inserted mold. In this position they remain until the operator has filled up another lot of molds.

The function of the fingers J is to engage into the folds of the bunching-apron near the ends, thereby to hold it properly distended 7c and provide against accidental disengagement, and it will be seen that as soon as the bunching-table is moved into the position shown in Fig. 5 the fingers, being freely hinged, are pushed back into the folds of the 75 bunching-apron by the marginal flanges C' on the segmental table C and remain there while the bunch is being rolled.

I wish to particularly point out some of the advantages which I obtain by my construction. First, the particular arrangement of the oscillating bunching-table with the apron passing over and around it on all sides disposes of the bunching-apron of good length in a very compact space, and at the same 85 time both ends are carried by the same yielding roller a, so that no portion of it can be unequally strained. The use of the guide-fingers J also permits the employment of a wider bunching-apron than ordinarily in use, 90 and thus my machine reduces the wear and tear on the bunching-apron to a minimum and makes its operation more uniform. It will be seen, further, that by the operation of the tightener-roll F the bunch is fully compressed in the pocket to its intended limit 95 before any part of the binder is pulled around it. This is a very important point in manufacturing proper bunches.

Having thus described my invention, what 100 I claim, and desire to secure by Letters Patent, is—

1. The combination with the bunching-roll, of a bunching-table adapted to be oscillated in proximity to said roll, a bunching-apron 105 in the form of an endless slack loop surrounding said roll and table, and having a pocket formed therebetween, in the initial position of the table, from the slack in said loop, a tightener-frame within said loop adapted to 110 be rocked outward to extend the loop and contract said pocket and yielding connection between said bunching-apron and table permitting of the tensioning of said apron on each side of said pocket by the action of said 115 tightener.

2. The combination with the bunching-roll an oscillating segmental bunching-table and a bunching-apron in the form of an endless slack loop surrounding said roll and table, 120 having a bunch-pocket formed from the slack in said loop, of a tightener rock-frame within said loop adapted to extend the same to contract said pocket, a take-up roll secured to said apron, and a rock-frame in which said roll is 125 rotatorily adjustably secured having a yielding connection to said bunching-table.

3. The combination with the bunching-roll, an oscillating segmental bunching-table, and a bunching-apron in the form of an endless 130 slack loop surrounding said roll and table having a pocket formed therebetween in the initial position of the table from the slack in said loop; of a binder-table having one edge

near said bunching-table at the forward edge of said pocket and extending outward therefrom, means for supporting and guiding said binder-table, and mechanism for moving said binder-table and bunching-table correspondingly in closing said pocket to bring the binder in position to be rolled around the bunch.

4. The combination with the bunching-roll, an oscillating segmental bunching-table and a bunching-apron in the form of an endless slack loop surrounding said roll and table having a pocket formed therebetween, in the initial position of the table, from the slack in said loop; of a binder-table having one edge near said bunching-table at the forward edge of said pocket and extending outward therefrom, means for supporting and guiding said binder-table mechanism for moving said binder-table and bunching-table correspondingly in closing said pocket to bring the binder in a position to be rolled around the bunch, and the presser-roll H, for the purpose described.

5. The combination with the bunching-roll, an oscillating bunching-table and the bunching-apron having a pocket for the bunch therein, and means for holding the apron whereby it can be drawn upon in order to roll the bunch in the pocket, of freely-swinging members, fingers carried by said members and projecting into said pocket from each side, and means for swinging said members whereby the fingers are adapted to guide the edges of the apron during the rolling of the bunch.

35 6. The combination with the bunching-roll, the oscillating segmental bunching-table and the bunching-apron having the pocket for the bunch formed therein, of freely-swinging fingers projecting into said pocket from opposite sides, and marginal flanges on said segmental table adapted to swing said fingers backward to form guides for the edges of said bunching-apron during the rolling of the bunch.

7. The combination with a drive-shaft adapted to run continuously and the actuating cam or wheel for the bunching mechanism loosely sleeved upon said shaft, of a clutch for coupling and automatically disengaging said cam or wheel and shaft, comprising a toothed wheel fixed upon said shaft, a dog secured to said cam or wheel and adapted to engage said toothed wheel, an annular track or camway with which said dog engages adapted to hold the latter in engagement with said toothed wheel to lock the cam and toothed wheel together and having an eccentric portion for disengaging said dog from said toothed wheel, and means for slightly rotating said track to force said dog from said eccentric portion of the track and thereby engage it with said toothed wheel.

8. The combination with the drive-shaft and the actuating cam or wheel for the bunching mechanism loosely sleeved thereon, of a toothed wheel fixed upon said shaft, a dog secured to said cam or wheel and adapted to en-

gage with said toothed wheel, an annular track or guideway with which said dog has a traveling engagement, having one or more eccentric portions for throwing said dog out of engagement with said toothed wheel, means for slightly rotating said track oppositely from the rotation of said shaft to force said dog from said eccentric portion and thereby cause it to engage with said toothed wheel and travel therewith until it again engages with said eccentric portion, and means for automatically rotating said track after the disengagement of said dog from said toothed wheel, to fully clear the former from the latter.

9. The combination with the drive-shaft and the actuating cam or wheel for the bunching mechanism loosely journaled thereon, of a toothed wheel fixed upon said shaft, a dog secured to said cam-wheel and adapted to engage with said toothed wheel, the disk R³ sleeved upon said shaft having an annular track or groove R² with one or more eccentric portions R⁵, the wrist-pin R⁴ on said dog having a traveling engagement with said track R², the link R⁶ and treadle-lever V connected with said disk R³, the arm R⁷, on said disk, the fixed stop R⁸ therefor, and the spring R⁹, all arranged substantially as and for the purpose described.

10. A cigar-bunching machine comprising a bunching-roll, a segmental bunching-table, a bunching-apron in the form of an endless slack loop surrounding said roll and table and having a pocket formed therebetween by the slack in the loop, means for holding the apron whereby it can be drawn upon in order to roll the bunch in the pocket, a tightener rock-frame within said loop and disconnected therefrom, and mechanism for intermittently rocking said table and tightener-frame, timed to first rock the table to close the pocket, then to rock said tightener to contract the pocket during the rolling operation of the apron and finally to move said table and tightener together to roll the bunch.

11. In a cigar-bunching machine, the combination with the frame and bunching mechanism supported thereon, of a mold-press adjacent to said bunching mechanism comprising a stationary lower platen K, the follower-plate N, operating mechanism therefor comprising a bar M connected to said follower and slidably secured in the frame, the drive-shaft P adapted to rotate continuously, the cams S and S' sleeved thereon, the former adapted to operate the bunching mechanism and the latter the bar M of the press mechanism, and a clutch for each of said cams S and S', each clutch adapted to couple and uncouple its cam with the drive-shaft and comprising a toothed wheel secured to the drive-shaft, a dog secured to its cam, a movable element having an annular track with which said dog engages adapted to hold the same in engagement with said toothed wheel, and provided with one or more eccentric portions, and a

treadle-lever for moving the said track element to disengage said dog from said eccentric portion or portions.

12. In a cigar-bunching machine, the combination of a bunching-roll, a rotary shaft, an oscillating segmental bunching-table having sleeves loosely engaging on said shaft, a gear secured to one of said sleeves, a bunching-apron in the form of an endless slack loop 5 surrounding said table and roll and having a bunch-pocket formed therebetween from the slack in the loop, a tightener for said apron-loop secured to said rotary shaft, a pinion secured to said rotary shaft, segmental racks 10 meshing with said pinions for operating the table and tightener, and mechanism for imparting the proper relative movement to said segmental racks.

13. The combination with a bunching-roll, 15 a bunching-table, a bunching-apron having a

pocket for the bunch therein and means for oscillating said table and apron, of a freely swinging member and a finger carried by said member projecting into said pocket from the side thereof and adapted to guide the edge of 25 the apron during the rolling of the bunch.

14. The combination with the bunching-roll and the apron having a pocket therein for the bunch, of a reciprocating bunching-table adapted to close said pocket in its initial movement and having an interval of rest after the closing of said pocket, and means for drawing upon said apron to contract the pocket during the interval of rest. 30

In testimony whereof I affix my signature 35 in presence of two witnesses.

ALEXANDER GORDON.
